UNITED STATES PATENT OFFICE.

HARRY CATLETT, OF LOS ANGELES, CALIFORNIA, ASSIGNOR TO SCHALK CHEMICAL COMPANY, OF LOS ANGELES, CALIFORNIA, A CORPORATION OF CALIFORNIA.

PAINT-DISSOLVER.

1,280,162.

Specification of Letters Patent.

Patented Oct. 1, 1918.

No Drawing.

Application filed April 24, 1917. Serial No. 164,234.

To all whom it may concern:

Be it known that I, HARRY CATLETT, a citizen of the United States, residing at Los Angeles, in the county of Los Angeles and State of California, have invented a new and useful Paint-Dissolver, of which the following is a specification.

This invention relates to compounds or mixtures for freeing or cleansing brushes, floors and other objects of paint, varnishes and other oil-containing preparations.

An object of the invention is to produce a mixture that can readily be used for the purposes specified without injury to the surfaces or objects to which it is applied.

Another object is to produce a cleansing compound which will not cause swelling of the wooden handle of paint brushes so as to avoid the subsequent shrinkage thereof and consequent cracking of the cement around the bristles and falling out of the bristles.

Other objects and advantages will be set forth hereinafter.

The cleansing compound is formed by combining or mixing together tri sodium phosphate (Na_3PO_4) and sodium chlorid ($NaCl$). Proportions found to be satisfactory in use are 93.25 per cent of the tri sodium phosphate and 6.75 per cent. of the sodium chlorid, though other proportions may be used to advantage.

The mixture thus formed may be put up in bulk or packages for the trade and when ready to use the mixture is dissolved in water of a volume that varies in accordance with the strength of the solution desired.

For cleaning brushes of paint or varnish ordinarily the mixture will be dissolved in water in the proportion of six quarts of water to one pound of the mixture.

It is preferable to first add part of the water warm, for instance, two quarts of warm water, so that the tri sodium phosphate will readily dissolve, and then add four quarts of cold water.

The solution is now ready for use. To clean a brush of paint or varnish the brush will be soaked in the solution until the paint or varnish in the brush is thoroughly loosened. The time required for this is generally from eight to thirty-six hours, de-

pending upon the condition of the brush. The tri sodium phosphate dissolved in the water hydrolyzes, the equation reading

The resulting sodium oxid or hydrate $NaOH$ saponifies the triglycerid (the vegetable oil in the paint or varnish), forming a sodium salt of the fatty acid which of course is soluble in water, the equation reading

The sodium phosphate precipitates all of the calcium and magnesium salts in the water as calcium and magnesium phosphates, thus softening the water the equations reading respectively

X stands for calcium or magnesium in the above equations.

The sodium chlorid increases the density of the water of the solution so as to minimize the penetrating power of the solution, thus insuring against swelling of the wood of the handle of the brush and subsequent shrinkage of the wood and cracking of the cement around the bristles and falling out of the bristles.

After soaking the brush as described above, the brush is then washed in the usual way with warm water and soap.

The brush is allowed to dry and then is rinsed in benzin, turpentine or the like to straighten out the bristles.

To clean brushes having shellac in them less water is used than above noted so that the solution will be stronger and the brushes are soaked longer than for cleansing them of paint or varnish.

It makes no difference whether the brushes to be cleaned have been used in paint, varnish or shellac or how long they have stood before cleaning except that the harder the paint, varnish or shellac has become the longer the soaking of the brushes is continued.

The solution does not affect the bristles in-

juriously, but softens the paint so that it may be readily removed with soap and warm water.

To clean pine or hard wood floors finished 5 with wax, shellac or varnish, desirable proportions are one pound of the mixture to five quarts of warm water to make a solution, which is then applied, preferably while warm, by a mop or cloth to the floor. The 10 solution is allowed to remain on the floor for a few minutes and then the wetted floor is scrubbed with a brush to loosen and dissolve the wax, shellac or varnish on the floor. The floor is then mopped with warm 15 water to remove the wax, shellac or varnish and the floor will then dry to its natural color and may be refinished, as desired.

Interior finish or woodwork may be cleaned by using a solution of which the 20 ingredients are in the proportion of one

tablespoonful of the mixture to one gallon of water. A sponge or soft cloth is moistened with the solution and rubbed on the surface to be cleaned which is then rubbed with a dry cloth. The surface thus cleaned 25 is then in perfect condition for refinishing.

I claim:

The paint dissolver described characterized in that it contains only tri sodium phosphate and sodium chlorid in substantially the proportions of 93.25 per cent. and 6.75 per cent. respectively, and sufficient water to dissolve the tri sodium phosphate and sodium chlorid. 30

Signed at Los Angeles, California, this 35
18th day of April, 1917.

HARBY CATLETT.
